(57) **CLAIM**

The ornamental design for a table, as shown and described.

DESCRIPTION

FIG. 1 is a perspective view of a table.

FIG. 2 is a plan view of the table of FIG. 1.

FIG. 3 is a left side view of the table of FIG. 1.

FIG. 4 is a right side view of the table of FIG. 1.

FIG. 5 is a front view of the table of FIG. 1.

FIG. 6 is a bottom view of the table of FIG. 1; and,

FIG. 7 is a rear view of the table of FIG. 1.

The broken lines depict portions of the table that form no part of the claimed design.

1 Claim, 7 Drawing Sheets
